Specification of Letters Patent. Patented Mar. 28, 1916.

Application filed August 24, 1914. Serial No. 858,256.

To all whom it may concern:

Be it known that I, CHARLES A. NELSON, a citizen of the United States, residing at Utica, in the county of Oneida and State of New York, have invented certain new and useful Improvements in Firearms, of which the following is a specification.

One object of this invention is to increase the facility of operation, reliability and general efficiency of the means for causing the transfer of the cartridges from the magazine to the breech of a gun of the type in which the cartridges are delivered from the magazine in a direction substantially longitudinal of the axis of the barrel, represented, for instance, in my Patent No. 1141256.

Another object is to provide a novel means for signifying to the operator that the magazine is empty on the firing and ejection of the empty shell of the last cartridge.

Another object is to provide for securing together the two receiver sections of a gun of the type of that represented in my application aforesaid in a way at once facilitating their ready assembling and disassembling and preserving the securing means intact with one of said sections when they are separated.

Another object is to improve the construction of and the manner of mounting a magazine of the tubular class in the gun.

The invention will be found fully illustrated in the accompanying drawings, wherein,

Figure 1 is a longitudinal sectional view of the receiver-portion of the improved gun, showing the transfer and other parts in the positions they occupy when the action slide is full forward and the hammer down; Fig. 2 is a similar view, showing the hammer cocked and the parts of the transfer mechanism in the positions they occupy when the action slide has partway advanced a cartridge into the breech; Fig. 3 is a similar view, showing the hammer and transfer parts in the positions they occupy when the last cartridge in the magazine has been fired and its shell ejected, the action being then locked; Fig. 4 is an inside elevation of the left-hand section of the receiver and the parts carried thereby; Figs. 5 and 6 are sectional views on lines $w-w$ and $x-x$ of Figs. 1 and 2, respectively; Figs. 7 and 8

are sectional views on line $y-y$ of Fig. 3, showing the receiver sections disassembled and assembled, respectively; Fig. 9 is an inside elevation of the left-hand receiver section and certain of its adjuncts, illustrating the manner of bringing a cartridge into alinement with the breech; Fig. 10 is a sectional view on the line $z-z$ of Fig. 9 and Fig. 10^a a sectional view at right angles to line $z-z$. Figs. 11, 12, 13, 14 and 15 are a top plan view, side, front and rear elevations, and an underneath plan, respectively, of the carrier; Fig. 16 is a side elevation of the carrier, partly in section; Figs. 17 and 18 are a left side elevation and an underneath plan of the rear part of the action slide; Fig. 19 is a view illustrating the magazine, partly in side elevation and partly in section; and, Fig. 20 is a sectional view on the line $v-v$ of Fig. 3.

The receiver or frame a comprises a stock section a' and a barrel section a'' which lie face to face when assembled, being interlocked by the mortise and tenon connections b , c and d , (Figs. 1 and 4) and held together preferably as follows: A sleeve e is driven with a tight fit into a hole in the section a' opposite a threaded hole f in the receiver section a'' , having in its end portion e' threading in the same pitch and being of the same diameter as the threaded hole f . g is a thumb screw provided with a milled head and having a threaded portion g' at the end thereof. When screw g , holding the sections together as shown in Fig. 8, is turned to clear its threaded portion from the threaded hole f and thus allow the sections to be separated it will not become detached from section a' unless it is now turned with its threading engaged with threading e' until it clears the sleeve.

h is the barrel and i the magazine tube, the same having the usual feeding aperture i' and having its rear end fitted into the receiver section a'' and being secured to the barrel by the straps or stirrups j in the novel manner illustrated in Fig. 20, wherein divergent holes k are shown formed in the under side of the barrel into which the ends j' of the strap are driven in such a way that when the joint is complete the strap tightly embraces the magazine tube. Telescoped into the tube i is the tube l having suitably secured in its outer end the milled head m affording an abutment for one end of the

spring n contained in the tube and normally pressing the cartridge plunger or follower o to a limit afforded by the contact of a shoulder o' thereon with a shoulder formed by 5 suitably contracting the inner end of the tube l , in which position, it may be remarked, said plunger or follower projects into the receiver as shown in Fig. 3. The head m has a wide groove m' formed in and 10 around it to afford a grip for the thumb and forefinger, and to lock the tube l against withdrawal when home I provide the spring-pressed catch p which is pivoted at its outer end in a longitudinal slot g in the 15 head and has a tooth p' on its inner end protruding through a hole l' in the tube and adapted to engage with one or the other of two diametrically opposite transverse slots i'' in the magazine tube i . If the catch p 20 does not at once lock the tube l when pushed home, a slight turn will bring the catch into registry with one or other of slots i'' ; the removal of the tube is accomplished quite as easily, because in rolling the head 25 m between thumb and forefinger the part of catch p which traverses the groove m' is pressed upon, releasing the catch.

r is the breech bolt, carrying the firing pin s and having on the right side the forwardly projecting spring-hook cartridge extractor t and on the left side lugs u adapted to receive the head of a cartridge between them, and also having the breech-up shoulder v , coactive with the fixed recoil shoulder 35 w , and the depending hoop-shaped lug x formed with opposite inclined surfaces x' and x'' .

y is the bar (having a sleeve z sliding on the magazine tube) of the action slide and 2 40 the sliding forearm fixed on said sleeve. The left side of the bar y has certain guiding surfaces to be described and also the stud 3 and hook 4. The breech-bolt has on the right side a depending flange r' by which 45 at its forward end it is supported on the bar y of the action slide, resting at the rear on stud 3 and being confined between the sections a' a'' of the receiver. When the action-slide is retracted stud 3 after some 50 lost motion impinges against surface x' of hook x and cams down the breech bolt out of breeched-up position, thereupon moving back the breech-bolt to the fully open position; when the action slide is advanced, 55 after some lost motion again, stud 3 impinges surface x'' , drives home the bolt and finally breeches it up.

The ejector 5, cushioned by a spring 6 inset in the groove 7 and held therein (Fig. 60 10^a) substantially as described in Patent No. 1100765, co-operates with the extractor t on the breech-bolt to throw out the empty extracted shell through the opening 8 in the right side of the receiver in a well known manner; in the present instance the ejector

carries a depending lug 9 having a function to be described in the positioning of the cartridge for breeching. In the forward and backward play of the bolt r the ejector is received in the usual groove r'' (Fig. 5) in the left side of the breech bolt, the device 5—9 as a whole being crowded back out of the way (against the tension of spring 6) as the breech-bolt reaches its forward limit by the contact of the edge r''' (Figs. 2 and 3) of the breech-bolt with the beveled rearward surface of lug 9.

10 is the hammer, 11 the usual spring-pressed thrust bar therefor, 12 the trigger, 13 a spring-pressed locking bar which holds the trigger against the notched surface 10' of the hammer, which latter is moved to the cocked position by hook 4 engaging a cam surface on the hammer; and 14 is a manually controlled hook-lever for locking 85 against retraction the action slide unless stud 10' on the hammer depresses the hook lever out of locking engagement with the notch y' of the action slide—i. e., in the forward or firing position of the hammer. 90

Those of the foregoing elements (excepting the novel means for securing together the two receiver-sections, the means for supporting the magazine tube, the means for releasably securing the spring-plunger-carrying tube l in the magazine tube, the plunger or follower o adapted to project into the space of the receiver upon explosion of the last cartridge and ejection of the shell thereof, and the device 5—9) that are not found 95 in the Savage Patent No. 839517 have been described and claimed in my Patent No. 1141256 before referred to and are therefore not claimed herein.

The transfer of the cartridges from the 10^a magazine into the breech is effected as follows: On the sleeve e is pivoted a cartridge carrier 15 having a curved depending wall 16 at its forward end and having a channel 17 formed in the top thereof, the forward 11 portion of which is somewhat elevated above the rear portion, producing a shoulder 18 which is preferably beveled. A pin 19 at the rear end of the channel forms a rearward stop for a cartridge coming to rest on the seat afforded by said channel. When the carrier is fully depressed, the cartridge in the magazine will be forced back by the spring plunger o onto said seat against the stop. At the right side of the forward part 120 of the cartridge seat 17 the carrier is formed with an upstanding wall 20 and in said side is inset a spring-cushioned lever 21 having a protruding stud 22.

Housed in a recess 23 in receiver section 125 a' and opposite wall 20 of the carrier there is fulcrumed on the horizontal pin 24 a lever 25 whose upper end is curved inwardly, being adapted when the carrier is depressed and exerts by its depending leg 15' cam- 130

ming pressure on the lever below its fulcrum 24, as at 26, to coöperate with wall 20 of the carrier to guide the cartridge in being delivered to the carrier and keep it on the seat 17 until other instrumentalities intervene to perform the latter function; when the carrier rises a spring 27 causes the upper end of the lever to swing back as in Fig. 6, out of the way of the carrier, as soon as the latter clears the lever 26.

It will be observed that the forward wall of the receiver forms on the inside a surface concentric with sleeve *e*, and that the butt end of the barrel forms a vertical surface. In furtherance of the object of keeping the nose of the cartridge moving parallel with these surfaces as it rises and thus finally bringing it as close as possible to the rear extremity of the breech, the butt of the elevated cartridge, as the latter passes into opposition to the butt surface of the barrel, comes against the stop 9 and, the carrier continuing to rise, said stop effects the forward shifting of the cartridge on the seat 17 until at the maximum elevation of the carrier the cartridge is held between the forward or high part of seat 17 and the top of the receiver, alined with the breech and with its nose close thereto (compare Figs. 9 and 2, the latter figure, however, showing the cartridge already partly advanced into the breech).

The carrier performs the upward movement followed by a downward movement in the forward thrust of the action slide; on the rearward thrust of the action slide it remains depressed. To accomplish this action the bar *y* of the action slide has a generally arched groove 29 formed in the left side thereof and adapted to receive the stud 22 of the carrier. This groove extends first at an upward incline, then horizontally, then at a downward incline, then horizontally again and finally at a downward incline again. It will be understood that the carrier is elevated, bringing the cartridge in line with the breech, then remains stationary until the advancing breech-bolt has advanced the nose of the cartridge into the breech, then partway descends so as to get out of the way of the breech-bolt, then again stands at a pause, its wall 16 blocking the magazine exit (this pause being desirable for preventing a fresh cartridge from entering the cartridge seat in such a way as to interfere with the cartridge being breeched, so possibly causing a jam, as by the interlocking of the rims of the two cartridges) and finally descends to its limit approximately coincidently with the driving fully home of the cartridge being breeched, thus admitting a fresh cartridge to the cartridge seat, these operations coinciding with the positions of stud 22 while engaged in the several portions, respectively, of the groove

29 above defined. The carrier, as stated, does not rise again until the next forward thrust of the action bar; in the return movement, therefore, stud 22 does not travel in the groove 29 but wipes over the lateral face 70 of the action bar adjoining the carrier, which face, at 30, is beveled down to the level of the bottom of the rear end of the groove 29. At the beginning and near the end of the groove 29 are formed the steps 75 31, over which the stud 22 snaps as the bar advances, the first preventing the return of the action slide once its advance has been fairly started, so that the carrier cannot be thus depressed and a possible jam caused by 80 the upending of the nose of the cartridge it carries by the butt of the next cartridge, protruding from the magazine, and the second preventing the stud 22 from traveling "backward" through the groove 29 (if perchance the carrier should be jarred out of its fully depressed position) on the backward movement of the action slide.

When the last cartridge has been fired the plunger *o*, on the full retraction of the action slide to reject the empty shell and the consequent full descent of the carrier, is forced by its spring back over the carrier and thus locks the action, signifying that the magazine is empty.

Having thus fully described my invention, what I claim as new and desire to secure by Letters Patent is:—

1. In combination, the barrel, the magazine, the receiver and means for shifting the cartridges from the magazine and then breeching the same including a movable carrier member and a reciprocable actuating member, said members having a back and forth camming connection alternately active 100 and inactive on the strokes, respectively, of the actuating member in each full reciprocating movement thereof and means to block the return movement of said actuating member during the stroke thereof when said connection is active.

2. In combination, the barrel, the magazine, the receiver and means for shifting the cartridges from the magazine and then breeching the same including a movable carrier member and a reciprocable actuating member, said members having the one an arched groove and the other a projection engaged in said groove, whereby on the stroke of said actuating member in one direction to cause back and forth movement of the carrier member, said groove having means engageable by the projection to block return movement of the actuating member during said stroke.

3. In combination, the barrel, the magazine, the receiver and means for shifting the cartridges from the magazine and then breeching the same including a movable carrier member and a reciprocable actuating

member, said members having the one an arched groove and the other a projection engaged in said groove, whereby on the stroke of said actuating member in one direction to cause back and forth movement of the carrier member, and also having means to block the actuating member against return movement during said stroke.

4. In combination, the barrel, the rearwardly discharging magazine below the same, the receiver, and means for shifting the cartridge from the magazine and then breeching the same including an up and down moving cartridge carrier member and a longitudinally reciprocating actuating member for the carrier member having an up and down camming connection with each other including a camming way in one member alternatively engaged and unengaged by the other member on the strokes, respectively, of the actuating member in each full reciprocating movement thereof and said members also having means to block the return movement of the actuating member during the stroke thereof corresponding to the engaged relation of said way and the member engageable therewith.

5. In combination, the barrel, the receiver, a back and forth moving structure having means to breech the cartridge, and an up-and-down moving carrier, said structure and the carrier having an up-and-down camming connection with each other and said connection having means to hold the carrier member at a pause during its stroke in one direction.

6. In combination, the barrel, the receiver, a back and forth moving structure having means to breech the cartridge, and an up-and-down moving carrier, said structure and carrier having an up and down camming connection active on the breeching stroke of said structure and said connection having means to hold the carrier member at a pause during downward movement thereof.

7. In combination, the barrel, the rearwardly discharging magazine below the same, the receiver, a back and forth moving structure having means to breech the cartridge, and a carrier movable upwardly into and downwardly out of obstructing relation to the magazine, said structure and carrier having an up and down camming connection active on the breeching stroke of said structure and said connection having means

to hold the carrier member at a pause during downward movement thereof.

8. The combination of the receiver, the barrel, means to breech the cartridge having means to extract the spent shell, said receiver having a shell ejecting opening, means for shifting the cartridge into position for breeching and a unitary device co-active with the shell extracting means to eject the shell and engageable by the cartridge to move the same in the shifting means while being shifted.

9. The combination of the barrel, the rearwardly discharging magazine, the receiver, backwardly and forwardly moving means to breech the cartridge, means for receiving the cartridge from the magazine and thereupon elevating and finally supporting the cartridge substantially aligned with the barrel and in position for breeching including a carrier having a cartridge seat and pivotally movable on a horizontal axis upwardly and rearwardly, said seat being inclined upwardly and rearwardly in the depressed position of the carrier and having its forward portion elevated above its rear portion, and means for shifting the cartridge on the carrier, while being elevated, forward clear of the rearward and onto the forward portion of the carrier.

10. A receiver for a gun comprising two sections arranged with portions thereof side by side, said portions having aligned holes of substantially equal diameter and both having substantially identical threading, and a headed screw entered from the outside through the hole of one section and having a threaded portion engaged with the threading of the hole of the other section. 95

11. In combination, the barrel, the rearwardly discharging tubular magazine below the same, the receiver, means to receive, elevate and thereupon breech the cartridge including an upwardly movable carrier, and means to lock the first means against movement consisting of an inflexible plunger arranged in and closely fitting the magazine and projectable therefrom for but a part of its length into locking engagement with the carrier. 100

In testimony whereof I affix my signature in presence of two witnesses.

CHARLES A. NELSON.
